(57) **CLAIM**

I claim the ornamental design for a flight system, as shown and described.

DESCRIPTION

FIG. 1 is a perspective view of a first embodiment of my new design for a flight system;

FIG. 2 is a top view thereof;

FIG. 3 is a front view thereof;

FIG. 4 is a rear view thereof;

FIG. 5 is a left side view thereof;

FIG. 6 is a right side view thereof;

FIG. 7 is a bottom view thereof;

FIG. 8 is a perspective view thereof in use on the body of a user of the flight system; and,

FIG. 9 is a perspective view of a second embodiment of my new design for a flight system.

The broken lines illustrate environmental structure and form no part of the claimed design.
